UNITED STATES PATENT OFFICE.

HERMAN ADLER, OF RICHMOND HILL, NEW YORK, ASSIGNOR, BY MESNE ASSIGNMENTS, TO BERSON & SCHLOSS, (INC.), OF NEW YORK, N. Y., A CORPORATION.

ATTACHMENT FOR PRODUCING SPIRAL STITCHES.

1,284,958.

Specification of Letters Patent. Patented Nov. 19, 1918.

Application filed October 17, 1917. Serial No. 197,095.

To all whom it may concern:

Be it known that I, HERMAN ADLER, a subject of the King of Roumania, residing at Richmond Hill, in the county of Queens 5 and State of New York, have invented certain new and useful Improvements in Attachments for Producing Spiral Stitches, of which the following is a specification.

My invention is designed for producing a 10 regulated spiral stitch upon rings of fabric for the purpose of stiffening them.

My invention is particularly applicable to sewing such reinforcing spiral stitching upon the rings or bands of drill that are 15 used for making sailors' hats. Sailors' hats have incorporated in them a ring or band of drill or similar material which is made by taking a long piece of fabric, overlapping its ends and fastening the overlapped ends 20 by stitching at right angles to the length of the strip. When these hats are washed the drill becomes limp so that the hat has an unsightly appearance and it is desirable to reinforce these rings or bands by a row of 25 spiral stitching which has been found satisfactory for this purpose.

Such work formerly has been done by hand, the operator feeding the band forward in the direction of its circumference 30 to the stitching mechanism of a sewing machine and at the same time moving the band transversely so that the stitching would be a spiral. This was slow and fatiguing work and rendered the hats expensive 35 because of the amount of labor required. In addition, said stitching was not uniform as it was impossible to produce a spiral stitch having a uniform pitch. According to my invention a simple and efficient 40 attachment is secured which is made up of standard parts and can be readily applied to certain well-known sewing machines at present on the market, which furnishes a spiral stitch of uniform pitch in an 45 automatic manner, so that the only labor required is to put the bands into place and to remove them. The pitch of the stitch can also be very minutely regulated and the 50 stitch can be started at any portion of the ring or band.

Other advantages and objects of my invention will be pointed out in the following description and drawings which illustrate one embodiment of my invention.

55 Figure 1 is a plan view,

Fig. 2 is a section on line 2—2 of Fig. 1, and

Fig. 3 is a section on line 3—3 of Fig. 2.

A countershaft 1, located underneath the bed of the machine drives a shaft 4 by means 60 of the worm gearing 2 and 3. The shaft 4, which has its bearings at 5 and 30 in suitable brackets, drives a threaded shaft 9, having its bearings in suitable brackets 8 and 10, by means of the worm gears 6 and 7. 65 The threaded shaft 9 is provided with a follower 12 which has a recess 26 of semi-circular shape and having a threaded interior which fits upon the threaded shaft 9 like half of a nut so that as the shaft 9 is rotated the follower 12 is caused to move toward the left. The follower 12 is secured to a slideable shaft 13, which has its bearing in brackets 11 and 10, by means of a set screw 14. The slideable shaft 13 has affixed there- 70 to a head 15, by means of a set screw 16. This head 15 has an arm 17 secured thereto.

At the left of the head 15 the shaft 13 has the bottom 23 of a holder for the ring or band of fabric secured thereto by means of 80 the head 19 and the set screw 20. This holder is made of resilient metal and is somewhat convex in shape and is preferably of the same width as the band or ring of fabric to be stitched. 85

The ring or band of fabric which is placed on top of the bottom member 23 of the holder is kept in place by means of an upper member 22 provided with a right angled extension 24 secured thereto. The bottom member 23 has vertical ears 48 secured thereto on each side, through which a pintle 21 is passed, so that it is impossible to move the upper member 22 to the left of the pintle 21, but the upper member 22 has a certain 95 free rocking movement with respect to the lower member 23.

The operation of my device is as follows:—

The operator, by moving the member 18 100 to the left, throws the driving clutch member 51, mounted on the rotating shaft 50, out of contact with the driven clutch member 52, mounted on shaft 1. The clutch member 51 rotates with shaft 50, but can be slid 105 thereon, and is urged to the right by spring 53. The member 18 slides in bearing 54. He then takes the ring of fabric which has been sewed together as before indicated, and places it so that a portion of its periphery 110

contacts with the top of the bottom member 23, of the holder. He then puts the upper member 22 and the pintle 21 into place. The band or ring of fabric is then held between the members 22 and 23, but not so strongly as to prevent the band from being fed forward by the feed dogs. The operator then tilts back the holder so as to upwardly rotate the follower 12 and move it out of mesh with the shaft 9. Then the operator takes the holder and moves it toward the right until the stitching mechanism 50 of the ordinary kind, as well as the feed dogs underneath the stitching mechanism, is in a line with any desired point of the ring or band which is now under it. The feed dogs are placed sufficiently close to the holder, to prevent any chewing or twisting of the fabric, at any time. The operator then, by tilting forward the holder, throws the follower 12 and the shaft 9 into mesh and by throwing the member 18 to the right, sets the machine into motion. The band or ring will be fed forward and pulled through the holder in a direction parallel to its plane by the feed dogs, and at the same time it will be moved transversely by the shaft 9, the follower 12 and the other parts indicated before. In this manner a very uniform spiral stitch is secured and when the arm 17 contacts with the member 18 and moves it to the left, the machine is automatically stopped. Any designated point of the band can be set into line with the stitching mechanism so that if a thread breaks, the stitching can be resumed at the point where the thread was broken.

The overlapped portions of the band or ring are, of course, of double thickness but this double thickness is accommodated by the advantageous construction of the holder. Thus, when the overlapping or double portion contacts with the front end of the upper member 22, it lifts it up by reason of the beveled shape of this end, and passes right through until it hits the rear end when the upper member 22 is rocked in the opposite direction and the doubled-over portion of the band passes out freely. At the same time the slight friction between the band and the holder maintains the upper member 22 against the pintle 21. The character of the stitch can be easily regulated by suitably changing the ratios between the various gears of the mechanism. Since the operation of the machine is absolutely automatic, any experienced person can attend to a number of machines so that the cost of labor is almost nothing.

I have described a preferred embodiment of my invention but it is clear that my invention is not limited thereto, as numerous changes could be made in its details without departing from the spirit of my invention.

I claim:

1. In combination with a stitching mechanism and the feed dogs of a sewing machine, a holder adapted to hold a band of fabric, the grip of said holder upon the said fabric being weaker than the grip of the feed dogs thereon, so that the feed dogs of the machine can pull the said fabric through the said holder, and means for uniformly moving the said holder in a line transverse to the line of stitch, the said holder comprising a portion above the fabric, and a portion below the fabric, both said portions being moved with the fabric held between them. 80
2. In combination with a stitching mechanism and the feed dogs of a sewing machine, a holder adapted to hold a band of fabric, said holder comprising an upper member and a lower member pressed against each other so as to grip the said fabric, the grip of the holder being weaker than the grip of the feed dogs, so that the feed dogs can pull the said fabric through the said holder, the upper member of said holder being vertically movable with respect to the lower member, and means for uniformly moving the said holder in a line transverse to the line of stitch, both said members being moved with the fabric between them. 90
3. In combination with a stitching mechanism and the feed dogs of a sewing machine, a holder for a band of fabric, comprising a lower member and an upper member, the said members being pressed against each other to hold the said fabric with a grip weaker than that of the feed dogs, so that the feed dogs can pull the said fabric through the said holder, the upper member of said holder being capable of a free rocking movement with respect to the lower member around an axis intermediate the ends of said holder, and means for uniformly moving the said holder in a line transverse to the line of stitch. 100
4. In combination with a stitching mechanism and the feed dogs of a sewing machine, a holder adapted to reevingly hold a band of fabric, said holder comprising a lower member at right angles to the direction of feed with vertical ears on each side, a pintle passed through said vertical ears at right angles to the line of stitch, and an upper member having a vertical lug adapted to bear against the said pintle, the said upper member having a free vertical movement with respect to the said lower member, the said feed dogs being adapted to pull said band through said holder. 115
5. In combination with a stitching mechanism and feed dogs of a sewing machine, a holder for a band of fabric, the grip of said holder upon said fabric being weaker than that of the feed dogs, so that the said feed dogs can pull the fabric through said holder, 120

a shaft upon which said holder is carried and mounted so as to have both a rocking movement and a longitudinal sliding movement, a second shaft having a threaded periphery and parallel to the first mentioned shaft, means for driving said second mentioned shaft, and a threaded member carried by said first mentioned shaft and adapted to mesh with the threadings on said second mentioned shaft, whereby the rotation of said second mentioned shaft causes a uniform sliding movement of the said first mentioned shaft and the said holder.

6. In combination with a stitching mechanism and feed dogs of a sewing machine, connecting means for connecting the said sewing machine to a source of power for driving the same, a holder adapted to hold a band of fabric with a grip weaker than that of the feed dogs, so that the feed dogs can pull the fabric through the said holder, means for uniformly moving said holder in a line transverse to the line of stitch, and disconnecting means operated by said holder for disconnecting the said connecting means from the source of power at a predetermined

5

point in the transverse movement of the said holder.

7. In combination with a stitching mechanism and the feed dogs of a sewing machine, 30 a holder adapted to hold a band of fabric with a grip weaker than that of the feed dogs, so that the feed dogs can pull the said fabric through the said holder, a shaft carrying said holder and mounted so as to have 35 both a rocking and a longitudinal sliding movement to a second shaft having a threaded exterior, operating means for operating said sewing machine and said second mentioned shaft, a member carried by 40 said first mentioned shaft and capable of being put into mesh with said threadings, so that the holder and the shaft are moved in a direction parallel to the length of the shaft, and a disconnecting arm operated by 45 said first mentioned shaft and capable of disconnecting the said connecting means at a predetermined point in the movement of the said holder.

In testimony whereof I hereunto affix my 50 signature.

HERMAN ADLER.
